UNITED STATES PATENT OFFICE.

ABRAHAM G. WEISER, OF LOS ANGELES, CALIFORNIA.

DESIGN FOR A TABLE-ORNAMENT.

47,369.

Specification for Design.

Patented May 18, 1915.

Application filed March 1, 1915. Serial No. 11,369. Term of patent 7 years.

To all whom it may concern:

Be it known that I, ABRAHAM GRANT WEISER, a citizen of the United States, residing at Los Angeles, in the county of Los Angeles and State of California, have invented a new, original, and ornamental Design for a Table-Ornament, of which the following is a specification, reference being had to the accompanying drawing, forming part thereof.

I claim:

The ornamental design for a table ornament, as shown.

A. G. WEISER.

Witnesses:

H. PACHETTE,
ELWOOD H. BARKELEW.
